LIFT ASSEMBLY FOR MOUNTING ON
SCAFFOLDING

Clifford L. Lutton, Washington, D. C.

Application October 29, 1951, Serial No. 253,719

9 Claims. (Cl. 254—145)

1

This invention relates to a lift assembly and particularly to a lift to be mounted on scaffolding for building construction or maintenance.

In the construction and maintenance of buildings, it is frequently desirable to have workmen suspended at various heights on the wall or other portions of the building. A sectionalized scaffolding support has been constructed which will allow workmen to construct scaffolding of any height or to be reached through any portion of a building. While working on such scaffolding, it is frequently desirable to elevate building materials, tools or other material onto the scaffold. Heretofore, such material has usually been lifted to the platform by means of ropes operated by the individual workman on the platform. It has long been recognized as desirable and many attempts have been made to produce lift devices operated from power sources on the ground for lifting material onto temporary scaffolding.

The present invention provides a lift assembly in which laterally extending arms are rigidly mounted on each of the upright standards of the scaffold and a sheave is mounted at the end of the arms so that a running line may be run through the sheaves and attached to a lift in the form of a power driven winch on the ground adjacent to the scaffolding. Pulleys are freely mounted on the running line between each of the sheaves and a retriever line is dropped to the ground so that a workman on the ground may pull the pulley down to the ground and attach a load, after which the winch will tension the running line and elevate the load to the workman on the top of the scaffold.

It is accordingly an object of this invention to provide an improved lift for scaffolding.

It is a further object of this invention to provide a power driven lift for elevating material onto scaffolding.

It is a further object of this invention to provide a means for attaching a lift to the top of scaffolding.

It is a further object of this invention to provide a lift means having rigidly spaced sheave mounts for operating a running line to lift material onto the scaffold.

Other objects and many of the attendant advantages of this invention will be apparent from the following detailed description taken in conjunction with the accompanying drawing, in which:

Figure 1 is a top plan view of the hoist in place on a scaffold;

Figure 2 is a front elevation of a scaffold showing the mode of operation of the hoist;

2

Figure 3 is an end elevation of a scaffold showing the assembly of the parts of the hoist on the scaffold;

Figure 4 is an enlarged perspective view of the base and attachment member of the hoist;

Figure 5 is an enlarged fragmentary top plan view showing the attachment of the brace to a scaffold;

Figure 6 is an enlarged cross sectional elevation through the arm and sheave attaching members, taken substantially on the line 6—6 of Figure 3;

Figure 7 is an exploded view, showing the mounting of the sheave;

Figure 8 is an enlarged perspective of the sheave attaching member;

Figure 9 is a perspective view of the rigidifying brace for maintaining the sheave mounting members in rigidly spaced relation to each other;

Figure 10 is an enlarged view partially broken away and in section showing the mounting of the lower pulley; and

Figure 11 is an enlarged perspective view of the load attaching pulley.

In the exemplary embodiment, a scaffold indicated generally at 10, has attached thereto the improved lift indicated generally at 12.

A satisfactory scaffold comprises a plurality of pre-assembled, pre-attached, individual sections

30 14 and, as best shown in Figure 3, these sections 14 each comprise a pair of vertically extending standards 16, 18 which are rigidly attached to each other by cross members 20 and 22. The standard members 16 and 18 are preferably of

35 a tubular construction, the top end thereof having telescoping pins 24 and 26. A scaffold of any height may be assembled by telescoping the standards 16 and 18 onto the pins 24 and 26 of a lower section. Pairs of standards produced by this tel-

40 escoping arrangement are laterally separated by any desired distance so that load members 28 and 30 may be mounted on the cross members 22 or 20 or intermediate cross pieces 32. Obviously,

45 any desired number of the cross pieces 32 may be utilized and they may extend completely across the members 16 and 18 or they may extend partially across and be supported in the middle by means of a vertically extending member 34. The sections 14 are longitudinally separated at any desired distance and are rigidly held in this spaced relation by means of cross braces 36 for detachable connection between the adjacent sections 14.

50 This construction provides a scaffold having a plurality of longitudinally rigidly spaced vertically extending standards 18, to which is rigidly attached cross members 20 and 22.

The hoist 12 includes a beam 40 rigidly attached to the base by one of the pairs of columns by any suitable means such as U-bolts 42. The beam 40 may conveniently be constructed of an angle iron having a flat side 44 secured against the standards 16 and 18 and a laterally extending top flange 46 having an opening 48 therein, in which is mounted a screw fastener, such as a bolt 50, on which is journaled a frame 52 of a pulley sheave 54, and the frame 52 is extended laterally alongside of the sheave 54 to provide a line guide so that a rope or line mounted on the sheave 54 will be prevented from jumping off the track of the sheave.

The top portion of the lift includes a brace member indicated generally at 56 and a sheave attaching member indicated generally at 58. The brace member 56 includes a laterally extending arm 60, preferably of angle construction, having a downwardly extending flange 62 and a horizontally extending flange 64. A base member 66 is rigidly connected to one end of the arm 60 and extends at right angles thereto. The base member 66 may be constructed either as an angle or as a channel member, as may be desired. A brace member 68 extends from the lower end of the base member 66 to a point adjacent the outer end of the arm 60. The brace member 68 is rigidly and permanently attached to both the arm 60 and the base 66. Suitable fingers 70 are mounted on the base member 66 and extend laterally therefrom to engage the standard 18. A connecting member 72 comprises a bar 74 rigidly attached to the side flange 62 of the arm 60 and extending longitudinally beyond the end of the arm 60, an angle member 76 rigidly attached to the bar 74 and has a top laterally extending portion 78 spaced from the end of the arm 60 a sufficient distance to provide a notch 80 for receiving the upstanding pin 26 of the standard 18 and contact of the portion 78 with the side of the standard pin 26 maintains the arm against lateral displacement from the standard 18. Downwardly extending portion 86 of the hook portion 82, extends over and embraces cross member 22 to prevent vertical displacement of the brace member along the standard 18.

A sheave supporting member 58 is preferably constructed from a channel member and has a downwardly extending flange 86 and a horizontally extending flange 88 respectively overlying the vertical flange 62 and the horizontal flange 64 of the brace arm 60. A downturned flange 90 is inturned at 92 to provide a hook member engaging the edges of the horizontal flange 64, as best seen in Figure 6.

An axle rod 94 is rigidly connected to the flange 86 by any suitable means, such as welding 96.

A plate member 100 has a transverse opening 102 therein and is mounted on the rod 94 and rigidly connected thereto by any suitable means, such as welding. The upper edge of the plate 100 is turned over to provide an angle portion 104 and journaled on the shaft 94 is a sheave 106. A second plate 108, provided with an opening 110, is freely mounted on the shaft 94 and the plate 108 has a flange 112 which overlies the flange 104 and the flanges 104 and 112 are secured together by any suitable means, such as the screw fasteners 114. Plates 100 and 108 closely embrace the sheave 106 and together with the flanges 104 and 112 provide a line guide for maintaining a line in contact with the sheave 106.

In order to maintain the brace and mounting

members 56 and 58 rigidly spaced with regard to each other, each of the sheave mounting means is provided with pins 116 and 118 rigidly secured to the top flange 88 of the sheave mounting member 58, a brace member 120, including a pair of rod members 122 and 124, are rigidly connected together in the middle by means of suitable means such as a rivet 126. The ends of the rods 122 and 124 are provided with eyes 130 for engaging the pins 116 and 118. Application of the brace 120 between adjacent pairs of bracing and attaching means rigidly space these means with respect to each other so that the application of the load between them will have no tendency to cause the brace members to sag together.

The running line 140 has a portion thereof wound on the drum 142 of a winch 144, having a driving motor 146 operatively connected to the winch 144. The line 140 extends from the drum 142 through the pulley 54 which is mounted on the beam 40 immediately below the sheave 106 mounted at the top of the standard 18, thence through the various sheaves 106 downwardly to a safety weight 150. Preferably, the safety weight 150 just exceeds in weight the maximum load that it is intended to raise by the lift. In this manner, any overrunning of the winch 144 will not cause undue stresses to be applied to the scaffold. Tensioning of the rope 140 by means of the winch 144 will thus raise any load that may be attached to the pulleys 152 freely mounted on the running line 140 between each of the sheaves 106 and if any of the tension should exceed that necessary to raise the load, it will be applied to lift the safety weight 150 and thus prevent undue strains on the structures until the motor can be shut off.

Each of the free running pulleys 152 comprises a frame 154 in which is mounted a sheave 156 and preferably the frame 154 extends laterally to the sides of the sheave 156 to provide a line guide to maintain the rope or other flexible cordage within the groove of the sheave 156. A plurality of attaching hooks 158 are connected to the frame 154 and may be arranged in any desired formation which is convenient to lift various articles from the ground to the platform. Usually, a retriever line 160 is connected to each of the pulleys 152 so that the pulley 152 may be pulled down to the ground to receive a load.

In order to prevent an unduly heavy load from moving the winch 144 or the scaffolding it is desirable to anchor the winch 144 with respect to the scaffolding and for this purpose braces 162, 164 are connected with the front corners of the winch to adjacent portions of the scaffolding and preferably are cross-connected and secured firmly together by means of a clamp 166.

In the operation of the lift according to the construction, the scaffold is built to the necessary height after which the platforms 28 and 30 are put in place. The brace members 56 are placed in position at the top of the standard 18 and the sheave attaching members 58 are attached thereto. The members 58 are prevented from sliding or otherwise being displaced longitudinally on the brace 56 by means of an upturned stop 170. The line 140 may be threaded through the sheaves 106 either before or after they are placed in position. To apply a load to the load lifting pulleys 152, the motor 146 is deenergized and the retriever line 160 is utilized to pull the pulley 152 to the ground lever, at which time any variety of load may be attached

to the hooks 158. The motor is then energized to tension the line 140 which lifts the load pulleys 152 to substantially horizontal relation to the sheaves 106 so that workmen in the top position of the scaffold may remove the load from the pulleys. Any overrun of the motor may be compensated by means of the safety weight 150 which will be lifted sufficiently to permit the excessive tension to be relieved.

While for purposes of exemplification, a particular embodiment of the invention has been shown and described according to the best present understanding thereof, it will be apparent to those skilled in the art, that many changes and modifications can be made therein, without departing from the true spirit of the invention.

Having described my invention, what is claimed as new is:

1. A hoist arrangement for use on a building scaffolding comprising a plurality of spaced apart sheave supports adapted to be mounted on the top of a scaffold, a sheave journaled on each of said supports, a pulley adapted to be mounted at the base of a scaffold, a winch, a running line on said winch and extending through said pulley and said sheaves in series relation, a load pulley freely mounted on said line between said spaced apart sheaves, the free end of said line being attached to a counterweight.

2. A hoist for lifting building material to a scaffold having laterally spaced vertical standards and vertically spaced horizontal cross members comprising: attachment members adapted to be mounted on said standards, each of said attachment members including a laterally extending arm, a channel member rigidly secured to said arm substantially perpendicular thereto, a brace between said arm and said channel member, means on said channel member embracing one of said vertical standards, a channel shaped hook rigidly mounted in spaced relation to said arm, said hook engaging one of said cross members adjacent to said one vertical standard, means for supporting a sheave at the end of said arm, a sheave mounted adjacent the base of said scaffold, a running line extending through said sheaves, a load engaging pulley mounted between said sheaves on said arms, a counterweight attached to one end of said line, a winch attached to the other end of said line.

3. A hoist for attachment to a scaffold having a plurality of pairs of spaced apart supporting standards, laterally extending cross members secured between the standards of a pair of standards, brace members maintaining said pairs of standards in predetermined spaced relation, said hoist comprising a sheave support at the top of each pair of standards, each sheave support including a laterally extending angle member, a base member rigidly secured in perpendicular relation to one end of said angle member, a brace extending between the outer ends of said base and said angle member, an angle shaped hook member rigidly attached to said angle member and spaced from the end attached to the base, a portion of said hook member engaging the side of one of said pair of standards, another portion of said hook engaging one of said cross members, fingers on said base engaging said one of said pair of standards, a sheave attaching member secured on said angle member, a shaft rigidly secured on said attaching member, a portion of a rope guide rigidly connected to said shaft, a sheave journaled on said shaft, a second rope guide portion engaging said

shaft and detachably secured to said first mentioned rope guide portion, a beam secured to an end pair of standards, a pulley pivotally mounted on said beam in vertical alignment with the sheave mounted at the top of said pair of standards, a winch, a line attached to said winch, said line extending through said pulley and said sheaves, the end of said line being connected to a counterweight, load engaging pulleys freely mounted on said line between said sheaves.

4. A hoist for elevating building material onto a scaffold having spaced apart pairs of standards, said standards having rigidly secured cross members extending therebetween, said hoist comprising a brace member on each pair of standards, hook means for attaching said brace member to a standard of said pair of standards and to one of said cross members, a sheave support detachably supported on said brace member, a rope guide mounted on said sheave support, a sheave in said guide, a beam rigidly secured on the base of an end pair of standards, a pulley swivelly mounted on said beam in vertical alignment with the sheave carried at the top of said end pair of standards, a running line extending through said pulley and said sheaves, load engaging pulleys freely mounted on said line between said sheaves mounted on said sheave supports, the end of said line extending through the pulley mounted on said beam being operatively connected to a winch, the other end of said line being connected to a counterweight, means for anchoring said winch with respect to said scaffold.

5. A hoist for attachment to a sectionalized scaffold support having spaced apart, aligned, sectionalized standards, platform supporting cross members on said standards and rigidifying members spacing said standards, said hoist comprising an arm for engaging one of said standards and one of said cross members in interlocking relation, brace means maintaining said arm in substantially perpendicular relation to said standard, said arm being an angle member, a sheave attaching member, said sheave attaching member including an angle member overlying said angle arm, the edge of said overlying angle being inturned to interlock with said arm, a stop on said arm to prevent longitudinal displacement of said overlying member, a sheave axle mounted on said overlying member, a sheave journaled on said axle, a pair of upstanding pins on said overlying member, cross braces mounted on the pins of adjacent overlying members to provide a rigid hoist structure.

6. A hoist for attachment to a sectionalized scaffold support having spaced apart, aligned, sectionalized standards, platform supporting cross members on said standards and rigidifying members spacing said standards, said hoist comprising an arm for engaging one of said standards and one of said cross members in interlocking relation, brace means maintaining said arm in substantially perpendicular relation to said standard, said arm being an angle member, a sheave attaching member, said sheave attaching member including an angle member overlying said angle arm, the edge of said overlying angle being inturned to interlock with said arm, a stop on said arm to prevent longitudinal displacement of said overlying member, a sheave axle mounted on said overlying member, a sheave journaled on said axle, a pair of upstanding pins on said overlying member, cross braces mounted on the pins of adjacent overlying members to provide a rigid

hoist structure, means for mounting a pulley on the base of the end standard of said scaffold support, a winch adjacent said end standard, brace means positioning said winch with respect to said scaffold support.

7. A hoist for attachment to a sectionalized scaffold support having spaced apart, aligned, sectionalized standards, platform supporting cross members on said standards and rigidifying members spacing said standards, said hoist comprising an arm for engaging one of said standards and one of said cross members in interlocking relation, brace means maintaining said arm in substantially perpendicular relation to said one standard, said arm being an angle member, a sheave attaching member, said sheave attaching member including an angle member overlying said angle arm, the edge of said overlying angle being inturned to interlock with said arm, a stop on said arm to prevent longitudinal displacement of said overlying member, a sheave axle mounted on said overlying member, a sheave journaled on said axle, a pair of upstanding pins on said overlying member, cross braces mounted on the pins of adjacent overlying members to provide a rigid hoist structure, means for mounting a pulley on the base of the end standard of said scaffold support, a winch adjacent said end standard, brace means positioning said winch with respect to said scaffold support, a running line, said line attached to said winch and extending through said pulley and said sheaves, a counterweight adjacent the end standard remote from said pulley, the free end of said line being attached to said counterweight.

8. A hoist for attachment to a sectionalized scaffold support having spaced apart, aligned, sectionalized standards, platform supporting cross members on said standards and rigidifying members spacing said standards, said hoist comprising an arm for engaging one of said standards and one of said cross members in interlocking relation, brace means maintaining said arm in substantially perpendicular relation to said one standard, said arm being an angle member, a sheave attaching member, said sheave attaching member including an angle member overlying said angle arm, the edge of said overlying angle being inturned to interlock with said arm, a stop on said arm to prevent longitudinal dis-

placement of said overlying member, a sheave axle mounted on said overlying member, a sheave journaled on said axle, a pair of upstanding pins on said overlying member, cross braces mounted

5 on the pins of adjacent overlying members to provide a rigid hoist structure, means for mounting a pulley on the base of the end standard of said scaffold support, a winch adjacent said end standard, brace means positioning said winch with respect to said scaffold support, a running line, said line attached to said winch and extending through said pulley and said sheaves, a counterweight adjacent the end standard remote from said pulley, the free end of said line being attached to said counterweight, pulleys freely mounted on said line between said sheaves, load attaching means on said pulleys.

9. A hoist arrangement for use on a building scaffolding comprising a plurality of spaced apart sheave supports adapted to be mounted on a scaffold, a sheave journaled on each of said supports, a pulley adapted to be mounted at the base of a scaffold, a winch, a running line on said winch and extending through said pulley and said sheaves in series relation, a load pulley freely mounted on said line between said spaced apart sheaves, the free end of said line being attached to a counterweight, said load pulley including a frame, a line guard for retaining said pulley on said line, a plurality of load engaging hooks on said frame, means attached to said pulley and extending to the ground for retrieving said pulley to attach a load thereto.
